CLAIM

The ornamental design for a record player, as shown and described.

DESCRIPTION

FIG. 1 is a perspective view of a record player, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is an enlarged view of area "8" in FIG. 1;

FIG. 9 is an enlarged view of area "9" in FIG. 1;

FIG. 10 is an enlarged view of area "10" in FIG. 1; and,

FIG. 11 is an enlarged view of area "11" in FIG. 1.

The broken lines shown in the drawings illustrate portions of the record player that form no part of the claimed design.

1 Claim, 11 Drawing Sheets
